US00D774600S

(12) **United States Design Patent** (10) **Patent No.:** **US D774,600 S**
(45) **Date of Patent:** **** Dec. 20, 2016**

(54) **ELECTRIC BALANCING SCOOTER**

(71) Applicant: **Hangzhou Notebike Technology Co., Ltd.**, Hangzhou, Zhejiang (CN)

(72) Inventor: **Xinwu Tao**, Hangzhou (CN)

(73) Assignee: **HANGZHOU NOTEBIKE TECHNOLOGY CO., LTD.**, Hangzhou, Zhejiang Province (CN)

(**) Term: **15 Years**

(21) Appl. No.: **29/538,849**

(22) Filed: **Sep. 9, 2015**

(30) **Foreign Application Priority Data**

Mar. 10, 2015 (CN) 2015 3 0056421

(57) **CLAIM**

I claim the ornamental design for the electric balancing scooter, as shown and described.

DESCRIPTION

The file of this patent contains a least one drawing executed in color. Copies of this patent with color drawings will be provided by the United States Patent and Trademark Office upon request and payment of the necessary fee.

FIG. 1 illustrates a front view of the electric balancing scooter;

FIG. 2 illustrates a rear view of the electric balancing scooter;

FIG. 3 illustrates a left side view of the electric balancing scooter;

FIG. 4 illustrates a right side view of the electric balancing scooter;

FIG. 5 illustrates a top view of the electric balancing scooter;

FIG. 6 illustrates a bottom view of the electric balancing scooter; and,

FIG. 7 illustrates a corner view of the electric balancing scooter.

1 Claim, 7 Drawing Sheets
(7 of 7 Drawing Sheet(s) Filed in Color)
